C. E. GODLEY,
PARABOLIC SECTIONAL REFLECTOR.
APPLICATION FILED SEPT. 17, 1917.

1,347,268.

Patented July 20, 1920.

UNITED STATES PATENT OFFICE.

CHARLES E. GODLEY, OF DETROIT, MICHIGAN, ASSIGNOR TO EDMUNDS AND JONES CORPORATION, OF DETROIT, MICHIGAN, A CORPORATION OF NEW YORK.

PARABOLIC SECTIONAL REFLECTOR.

1,347,268.

Specification of Letters Patent. Patented July 20, 1920.

Application filed September 17, 1917. Serial No. 191,684.

To all whom it may concern:

Be it known that I, CHARLES E. GODLEY, a citizen of the United States, and residing at Detroit, in the county of Wayne and State 5 of Michigan, have invented a new and Improved Parabolic Sectional Reflector, of which the following is a specification.

Various efforts have been made heretofore to prevent glare in automobile headlights 10 by forming the upper half of the reflectors of a shape different from the lower half, the thought being generally to project the rays from the lower half directly ahead in substantially parallel relation to each other 15 and to direct those from the upper half downwardly and divergently over the roadway relatively close to the vehicle, thus preventing any beams from rising above the longitudinal horizontal plane of the bulb. In 20 all such instances of which I am aware, however, the construction has been such as prevented manufacture by commercial processes, particularly in that the finishing and buffing had to be done by hand.

25 The primary object of the present invention is to produce a headlight reflector, which can be made at substantially the same cost as the ordinary well known parabolic type, whereby all objectionable glare is prevented 30 and whereby the light is efficiently directed over the roadway without the formation of bands or shadows. To this end, it consists in a reflector, the lower half of which is substantially a standard parabolic surface, 35 whereas the upper half is formed of a series of parabolic sectors the transverse cross sections of which are surfaces of revolution about the axis of the reflector and the foci of which are located rearwardly from the 40 focus of the lower half. In use the source of light is positioned in the last mentioned focus. It also consists in a reflector the main portion of the surface of the lower half of which is parabolic, said lower half being 45 provided, near its rear end, with one or more parabolic sectors having a focus forward of the focus of the main portion.

The invention further consists in a method 50 for forming the reflector wherein the blank is first stamped and finished substantially into the shape of a paraboloidal surface, afterward stamped a second time to offset the parabolic sectors therefrom, and finally subjected to buffing while turning around its 55 axis about a rotating tool.

In the drawings, Figure 1 is a vertical transverse section through a preferred embodiment of the invention, and Fig. 2 is a front view corresponding thereto, but somewhat reduced.

The reflector is formed of a continuous sheet metal stamping 1 the lower half of which is preferably substantially the same as the lower half of an ordinary parabolic reflector having the longitudinal axis 2 and the focal point 3, thus forming the parabolic reflecting surface 4 from which the reflected rays of a filament 5 are directed forwardly in substantially parallel relation to one another, as indicated at 6. The upper half of 70 the reflector is made up of a series of parabolic sectors 8, 9, 10, 11, etc. (nine being shown, although the number may vary), having a common focus 20 located on the axis 2 rearwardly from the focus 3. Preferably, the central transverse section of each of the sectors is located on an extension of the parabolic surface 4; in other words, planes perpendicular to the axis 2 and passing through the middle of the corresponding 80 parabolic sector intersect the reflector in complete circles. Because of the relative locations of the foci 3 and 20, all rays emanating from the filament located in the former and reflected by the sectors are directed 85 downwardly and diffused over the roadway as indicated at 21.

It will be observed that the rear edges of the sectors 8, 9, 10, etc., are offset slightly outwardly and the front edges are offset 90 slightly inwardly from the imaginary parabolic surface of revolution corresponding to the lower half of the reflector. It is important that the front edge of each sector project sufficiently to prevent light from the 95 filament from striking the surfaces whereby the particular sector is joined to the next forward sector, as glare would otherwise tend to result.

It is found that the rays reflected from 100 that portion of the standard parabolic reflector just below and rearwardly from the bulb also tend to cause glare. To prevent this action, this surface may be offset from the main paraboloid to form one or more 105 parabolic sectors 25, 26, the foci of which are located at a point 28 somewhat forward of the focus 3. Putting it another way, the rear edge portions of the sectors 25, 26 are offset inwardly and the forward edge por- 110

tions are offset outwardly from the extended surface of the main paraboloid. Rays striking the surfaces 25, 26 are therefore diffused downwardly over the road surface as indicated at 29.

The purpose of arranging the foci of the sectors 8, 9, 10, etc., at a single point, and the foci of the sectors 25, 26 at a single point, is to prevent the formation of alternating belts of light and shadows in the roadway—in other words, to spread the light uniformly.

In the manufacture of the reflector, the metal is first stamped by dies to form a full parabolic sheet or cup of the same curvature as the main portion of the lower half. This blank is then held in a suitable finishing machine (not shown) whereby it is rotated about the axis 2, and while so rotating is subjected to the action of a hard finishing or cutting tool 30 which turns counterclockwise at high speed about an axis perpendicular to the plane of the paper (Fig. 1). Relative movement is simultaneously given the tool and blank along a parabola 31 (parallel to the parabola whereby the surface 4 is generated), thus cutting the inner surface of the latter to true paraboloidal shape, as is common practice in the manufacture of ordinary parabolic reflectors. Thereafter the blank is again placed in suitable dies and pressed to offset the metal sufficiently to form the parabolic sectors 8, 9, 10, etc., and the sectors 25, 26 (if the latter are used) in a single operation. Because the bending incident thereto is very slight it is unnecessary to further cut the inner surfaces of the sectors 8, 9, 10—25, 26, the final buffing operation taking place by substituting a wheel having a soft exterior for the cutting tool 30 and again subjecting the blank to the action of the finishing or buffing machine as before. The buffing tool, being soft, conforms to the inner surface of the sectors substantially as well as to the surface 4. In this manner the reflector can be made wholly by machinery, no hand finishing or buffing being required, the whole operation being the same as ordinary practice except the added step of offsetting the parabolic sectors between the steps of cutting and buffing.

I claim:—

1. A reflector having upper and lower halves, the reflecting surface of the main portion of the lower half of the reflector conforming to a true paraboloid, the upper half of the reflector including a plurality of sectors of paraboloidal surfaces, each sector of the upper half having its own focal length, the foci of the sectors being substantially at a common point which is located rearwardly from the focus of the main portion of the lower half of the reflector.

2. A reflector comprising an upper por-

tion and a lower portion, the inner face of the lower portion being a paraboloidal surface, the inner face of the upper portion including a plurality of narrow transversely extending strips of different paraboloidal surfaces, the foci of the last mentioned surfaces being rearward of the focus of the first mentioned surface.

3. A reflector having two portions located at different levels, said reflector having a longitudinal axis, the inner face of one of the portions being a paraboloidal surface, the inner face of the other portion including a plurality of narrow transversely extending strips of different paraboloidal surfaces, said strips being slightly offset from one another and having foci spaced from the focus of the first mentioned surface longitudinally of the reflector.

4. A cup shaped reflector formed of thin sheet metal, the upper portion of the reflector including a plurality of transversely extending strips of paraboloidal surfaces offset slightly from each other and having different focal lengths, the foci of said surfaces substantially coinciding with each other.

5. In combination, a sheet metal reflector having an upper portion, a lower portion, and a longitudinal axis, the lower portion constituting substantially the lower half of said reflector and having its inner face conforming to the surface of a paraboloid the focus of which lies substantially on the longitudinal axis, the upper portion constituting substantially the upper half of the reflector and having its inner face formed of a plurality of substantially parallel narrow transversely extending strips conforming to the surfaces of different paraboloids, the portion of each of the surfaces which has the greatest diameter being forward and the foci of said last named paraboloidal surfaces being rearward of the first mentioned focus.

6. A parabolic reflector having a longitudinal axis, the reflector being so constructed that the trace of the vertical plane which includes the axis with the inner surface includes in its upper half a series of short sections of forwardly diverging parabolas, said trace including in its lower half a longer section of a parabola, planes perpendicular to the axis and passing through substantially the mid-point of said first mentioned sections intersecting the last named section at the same distance from the axis as they do the corresponding one of said first named sections.

7. A cup-shaped reflector having a central portion comprising a plurality of concentric paraboloidal rings, the outer ring being offset rearwardly from the inner, the remainder of the reflector consisting of an

upper and a lower portion divided by a central horizontal plane, the inner face of the lower portion being a paraboloidal surface, the inner face of the upper portion 5 consisting of a plurality of narrow transversely extending strips, of even widths throughout their lengths, of different paraboloidal surfaces, the foci of the last mentioned surfaces being rearward of the focus 10 of the lower forward portion of the reflector.

8. A reflector comprising an upper por-

tion and a lower portion meeting in a horizontal plane which passes through the axes of the reflector, the inner face of the lower 15 portion being a paraboloidal surface, the inner face of the upper portion including a plurality of narrow transversely extending strips of different paraboloidal surfaces, said strips being of even widths 20 throughout their lengths, the foci of said strips being rearward of the focus of the first mentioned surface.

CHARLES E. GODLEY.
